LATCH FOR ADJUSTABLE BACK CHAIRS

Filed April 26, 1947

FIG. 2

INVENTOR
PETER H. MERSINGER

BY *J. H. Cook*
ATTORNEY

Turned to the right, the chair back is tilted, and as it is tilted, the inverted U-shaped member 3 is rotated clockwise, as indicated by the arrow, and the ball 13 is moved forward, as indicated by the arrow, so that the ball 13 is moved into the inverted U-shaped member 3, and the ball 13 is held in gripping engagement with the sides 5 of the inverted U-shaped member 3.

As the ball 13 is moved forward, the rod 14 is moved forward, as indicated by the arrow, so that the rod 14 is moved into the housing 1, and the rod 14 is held in screw-threaded engagement with the housing 1.

UNITED STATES PATENT OFFICE

LATCH FOR ADJUSTABLE BACK CHAIRS

Peter H. Mersinger, St. Louis, Mo., assignor to National Machine Company, St. Louis, Mo., a corporation of Missouri

Application April 26, 1947, Serial No. 744,207

4 Claims. (Cl. 155—159)

1

This invention relates to chair latches, and particularly to such a device for use on the type of chair which is used in beauty shops, or the like, where it is necessary that the chair back be tiltable to various angles and then locked in position. The principal advantages of my new latch are its high degree of efficiency in guarding against inadvertent displacement of the chair back once it has been locked in tilted position, and the simplicity of its construction and operation.

In the drawings

Fig. 1 illustrates the seat and back of a chair equipped with my latch, showing the latch as it appears with the chair back in normal sitting position in full lines, and in dash lines when the chair back is in tilted position.

Fig. 2 is an enlarged cross-sectional view, partly broken away, also showing the latch as it appears with the chair back in normal position in full lines, and in dash lines when the chair back is in tilted position.

Fig. 3 is a view taken on line 3—3, Fig. 2, illustrating the latching mechanism.

Fig. 4 is a view taken on line 4—4, Fig. 2, illustrating the means for operating the latching mechanism.

Fig. 5 is a perspective view showing the wedge faces on the slideable element of the latch.

The invention includes the latch itself and means associated therewith for operating it, and for convenience in preparing this application I have illustrated and will describe the invention in engagement with a chair, which includes the usual seat A, back B, arms C, and a frame D connecting said back and arms.

I will first describe the latch itself, which comprises a U-shaped housing 1 having a top closure 2 which is rigidly secured to the underside of the arm C of the chair, and pivotally secured to the frame D, as at E. An inverted U-shaped member 3 is longitudinally slideable within the housing 1, and is so positioned that its upper, curved end 4 contacts the closure 2, while its sides 5 depend vertically to a point about midway of the housing 1. From the point 6 the inverted U-shaped member 3 is reduced, so that at its rearmost end it is of smaller diameter than at its forward end, as will be most easily understood from a comparison of Figs. 3 and 4 in which this member is clearly seen. Beginning at the point 7 the inverted U-shaped member has a peculiarly shaped portion 8, as shown most clearly in Fig. 2. The housing 1 is approximately the length as the arm of the

chair to which it is attached, but the inverted U-shaped member 3 is considerably longer and extends rearwardly beyond the chair arm, being secured to the chair back B by a rotatable shaft 9. At the forward portion of the inverted U-shaped member 3, its sides 5 are cut diagonally as shown in dash lines at 10 in Fig. 2.

Extending forwardly from the point 6, an elongated member 11 is positioned within the inverted U-shaped member 3, and the member 11 is surrounded by a coil spring 12. A ball 13 is positioned adjacent the forward end of said spring, said ball being of such diameter that it extends a slight distance between the vertical sides 5 of the inverted U-shaped member 3, in such manner that the spring 12 acts to wedge said ball rightly between said sides 5, where it is held in gripping engagement.

A rod 14 extends from the front of the inverted U-shaped member 3 rearwardly to the chair back, said rod being partly within and partly outside of said member and being slideable therewith. At its forward end the rod has a downturned hook 15 against which the ball 13 abuts (Fig. 2), and said rod is slideable with respect to the housing 1.

I will now proceed to the means for operating the latch above described:

A circular element 16 is mounted on the shaft 9, and said circular element is provided with a central cut-out portion 17 so that the element 16 includes a horizontal upper portion 18 and a pair of vertical wings 19 extending downwardly therefrom in such a manner that the peculiarly shaped portion 8 previously referred to is positioned between the vertical wings 19. A screw 20 connects the element 16 with the shaft 9 so that said element is rotatable with said shaft, and for facilitating rotation of these parts I provide a grasping handle 21 which is screwed into the element 16, as at 22. A U-shaped member 23 is rigidly secured between the wings 19 by a pin 24, and the rod 14 is rigidly held in screw-threaded engagement with said member 23, as shown at 25, so that the member 23 and the rod 14 are movable upon rotation of the element 16.

In operation the procedure is as follows:

Suppose the chair is in normal sitting position, as shown in full lines in the drawings, and is to be moved to the tilted position shown in dash lines. The handle 21 is grasped by the operator and moved forwardly, as shown by dash lines in Fig. 2, thus rotating the circular element 16 with the shaft 9. This rotation of the element 16 has the effect of moving the U-shaped element 23

to the position shown in dash lines, which draws the rod 14 in a backward direction through its connection with said element 23. As the rod 14 is drawn backwards, its hook 14 draws the ball 13 back with it against the coil spring 12 until said ball rests against the elongated member 11, as shown in dash lines in Fig. 2, so that the ball is drawn out of gripping engagement between the diagonally cut portion 10 of the sides 5 of the inverted U-shaped member 3, and consequently the latch is in unlocked position.

The operator now draws the chair back rearwardly to the degree at which he wishes it to be tilted, while continuing to hold the handle 21 in its forward position. When the chair back has been placed at the desired angle, he releases the handle 21 and consequently the circular element 16 and the rod 14, whereupon the action of the coil spring 12 against the ball 13 pushes said ball forward into its original gripping engagement between the diagonally cut portions 10 of the sides 5 of the member 3, and said ball carries with it the hook 15 to its original position. The gripping engagement between the ball and the member 3 is now again operative to lock the parts in position against slipping, with the chair back in the tilted position shown in the dash lines.

While I have described this invention as being applied to one arm of a chair, it is to be understood that a pair of the chair latches will be used, one on each arm of the chair, and the operator will stand behind the chair so that he can grasp both of the handles 21 simultaneously.

The same procedure as described above for tilting the chair backwards will be followed when it is to be returned to its normal, upright position.

I claim:

1. A chair latch in engagement with an adjustable chair and comprising an elongated, hollow, normally horizontal member secured to the arm of said normally horizontal chair and an element slidable within said member and secured to the pivoted back of said chair, means associated with the back of said chair for instituting sliding motion of said slidable element, a spherical spring-controlled part in gripping engagement with wedge faces on said slidable element and a rod having a downward hooked end portion within said slidable element for moving said spherical spring-controlled part out of such gripping engagement to permit adjustment of the back of said chair, said rod also being associated with and movable by the means on said chair back for instituting sliding movement of said slidable element, said gripping engagement being defective to hold the back of said chair in adjusted position.

2. A chair latch in engagement with an adjustable chair and comprising an elongated, normally horizontal housing secured to the arm of said chair and an element slidable within said housing and secured to the pivoted back of said chair, means rotatably mounted on the back of said chair and rigidly associated with said slidable element for instituting sliding movement of said slidable element, a rod having a downward

hooked end portion within said slidable element and rigidly secured to said rotatable means, a spherical spring-controlled part in gripping engagement with wedge faces on said slidable element and in contact with said rod and adapted to be released from such gripping engagement upon rotation of said rotatable means simultaneously with the sliding of said slidable element to permit adjustment of the back of said chair, said gripping engagement being effective to hold the back of said chair in adjusted position.

3. A chair latch in engagement with an adjustable chair and comprising an elongated, normally horizontal housing secured to the arm of said chair and an element slidable within said housing and secured to the pivoted back of said chair, means rotatably mounted on the back of said chair and rigidly associated with said slidable element for instituting sliding movement of said slidable element, a rod having a downward hooked end portion and being positioned within said slidable element and rigidly secured to said rotatable means, a spherical spring-controlled part in gripping engagement with wedge faces on said slidable element and in contact with said rod and adapted to be drawn out of such gripping engagement by the downward hooked end portion of said rod upon rotation of said rotatable means simultaneously with the sliding of said slidable element to permit adjustment of the back of said chair, said gripping engagement being effective to hold the back of said chair in adjusted position.

4. A chair latch in engagement with an adjustable chair and comprising an elongated, normally horizontal housing secured to the arm of said chair and an inverted U-shaped element slidable within said housing and secured to the pivoted back of said chair, a rotatable shaft secured to the back of said chair and means mounted on said shaft and rotatable therewith and rigidly associated with said inverted U-shaped element for instituting sliding movement of said element upon rotation of said shaft, a rod provided with a downward hooked end portion and being positioned within said inverted U-shaped element and rigidly secured to said rotatable means, a spring-controlled ball in gripping engagement with the legs of said inverted U-shaped element and adapted to be drawn out of such gripping engagement by said downward hooked end portion upon rotation of said shaft simultaneously with the sliding of the inverted U-shaped element to permit adjustment of the back of said chair, said gripping engagement being effective to hold the back of said chair in adjusted position.
